UNITED STATES PATENT OFFICE

JAMES R. FLETCHER, OF STAMFORD, CONNECTICUT, ASSIGNEE TO THE YALE & TOWNE MANUFACTURING COMPANY, OF STAMFORD, CONNECTICUT.

LOCK.

No. 904,860.

Specification of Letters Patent.

Patented Nov. 24, 1908.

Application filed April 29, 1908. Serial No. 429,849.

To all whom it may concern:

Be it known that I, JAMES R. FLETCHER, of Stamford, in the county of Fairfield and State of Connecticut, have invented certain new and useful Improvements in Locks; and I do hereby declare the following to be a full, clear, and exact description of the invention, such as will enable others skilled in the art to which it appertains to make 10 and use the same.

My invention relates to an improvement in locks, of that type which is master keyed by a tumbler which lifts all the other tumblers. In locks of this type the spring pressure of the several tumblers, is transmitted to the lifter tumbler, thus causing the latter to tip sidewise, or in a direction to force the other tumblers off the post supporting the several tumblers, when the cover plate of 20 the lock is removed, and the object of my invention is to provide means for preventing the tipping movement of the lifter plunger.

With this end in view my invention consists in the parts and combination of parts as will be more fully described and pointed out in the claims.

In the accompanying drawings, Figure 1 is a view in elevation of a lock embodying 30 my invention. Fig. 2 is a similar view, the cover plate being removed. Fig. 3 is a view showing the bolt, the tumblers being removed. Fig. 4 is a view of the lifter tumbler. Fig. 5 is a view of the change key and

Fig. 6 is a view of the master key.

While I have shown and will describe the improvement in connection with a cabinet lock, I would have it understood that I do not limit its use to such locks, as it may be 40 applied to any lock employing a lifter tumbler such as is herein shown and described.

1 represents the lock case, provided with a cover plate 1^a which conceals the tumblers and holds the latter in place on their bearing post 2, and 3 is the sliding bolt, slotted at its inner end to embrace the post 2, and be guided by the latter, and provided at a point in rear of its head, with the fence 4, which coacts with the tumblers to lock 50 and release the bolt.

5 is the lifter tumbler, provided with the lug 6, which latter passes through slots in the other or change key tumblers 7, and

operates, when lifted by the master key, to lift all the change key tumblers and align 55 the gates of the latter with the fence 4 on the bolt, so that the latter may be retracted by the master key.

Heretofore in locks having lifter tumblers, the latter have been mounted on the 60 post on which the change key tumblers are mounted, hence the lifter tumbler has had a bearing equal to the thickness of the tumbler itself, and as the spring pressure from all the tumblers 7 is transmitted to the lifter 65 tumbler, through the lug 6, which as before explained passes through slots in the several tumblers 7, there is a lateral pressure transmitted to the lifter tumbler 5 which tends to tilt sidewise, or in a direction to force the 70 other tumbler 7 off the post supporting the several tumblers, when the cover plate of the lock is removed.

In the present instance I provide the lifter tumbler 5 with a fixed sleeve 8 of sufficient 75 length to pass through all the change key tumblers 7 and form the bearing therefor. This sleeve is mounted on bearing post 2, and provides an elongated bearing for the lifter tumbler, and a bearing for all the 80 change key tumblers. This elongated bearing prevents any lateral tipping of the lifter tumbler, hence there is no pressure on the change key tumblers tending to force the outer change tumblers off their bearing post 85 when the cover plate of the casing is removed.

The lifter tumbler 5 is provided with a gate of sufficient size to permit the fence on the bolt to enter when in its normal position, 90 that is with its end resting against the fence, or when moved to its extreme position by the master key 9. The change key 10 is so constructed to engage all the tumblers but the lifter tumbler, hence when the tumblers 95 have been set by such key, the further movement of the key retracts the bolt in the usual manner, the fence on the bolt moving into the gates in the several tumblers.

The master key 9 is cut away opposite all 100 the tumblers engaged by the change key 10 and operates to engage the lifter tumbler only and the latter acting through the lug 6, operates to lift or move all the tumblers 7 until the gates therein align with the fence. 105

The keys are guided by the rotary slotted

key post 11 mounted in the case and supported by and between the two side faces thereof.

The several tumblers except the lifter tumbler are each provided with a spring 12 which tends to hold the tumblers in position to prevent the bolt from being retracted.

Having fully described my invention what I claim as new and desire to secure by 10 Letters-Patent, is:—

1. The combination with a lock case and a post therein, of a lifter tumbler, a tubular bearing projecting from said tumbler, the said bearing being mounted on a post, and a 15 change key tumbler mounted on said tubular bearing.

2. The combination with a lock case and a post therein, of a bolt having a fence, a lifter tumbler, a bearing sleeve carried by

said lifter tumbler and mounted on the post, 20 and a series of change key tumblers mounted on said projecting bearing sleeve.

3. The combination with a case and a post therein, of a lifter tumbler, a lug projecting therefrom, a bearing sleeve carried by the 25 lifter tumbler and mounted on the post, and a series of change key tumblers mounted on the sleeve, each change key tumbler having a slot for the passage of the lug on the lifter tumbler.

In testimony whereof, I have signed this specification in the presence of two subscribing witnesses.

JAMES R. FLETCHER.
